UNITED STATES PATENT OFFICE.

LEWIS LEWISON, OF HAMILTON, ONTARIO, CANADA.

BATTER-FEEDING MECHANISM FOR ICE-CREAM-CONE-MANUFACTURING APPARATUS.

1,309,862.

Specification of Letters Patent. Patented July 15, 1919.

Original application filed October 19, 1917, Serial No. 197,502. Divided and this application filed September 19, 1918. Serial No. 254,822.

To all whom it may concern:

Be it known that I, LEWIS LEWISON, of the city of Hamilton, county of Wentworth, Province of Ontario, Canada, have invented 5 certain new and useful Improvements in Batter - Feeding Mechanism for Ice - Cream - Cone-Manufacturing Apparatus, of which the following is a specification.

The invention disclosed herein relates to 10 apparatus for feeding batter into the molds of a machine such as described and shown in my co-pending application No. 197502, filed October 19th, 1917, of which this present application is a division, and my object is to 15 devise a batter-feeding device which is readily placed in position or removed from the machine, which is easily disassembled and cleaned, and which is adapted for coöperation with the molds so that no batter is fed 20 to a mold unless the mold is properly closed and locked.

I attain my object by means of the constructions hereinafter described and illustrated in the accompanying drawings in 25 which—

Figure 1 is a side elevation of the batter feeding mechanism with a mold in position underneath the same;

Fig. 2 an end elevation of the parts shown 30 in Fig. 1;

Fig. 3 is a side elevation of the batter feeding device removed from its supports;

Fig. 4 an end elevation of the same, partly 35 in section;

Fig. 5 a plan view of the same;

Fig. 6 an end elevation of the same;

Fig. 7 a detail in side elevation illustrating 40 the means of supporting the batter feeding device and the device for throwing it out of action;

Fig. 8 an end elevation of the same parts looking from the inner right side; and

Fig. 9 a similar view looking from the outer side; and

Fig. 10 an end elevation of the parts shown 45 in Fig. 2 showing the mold unlocked; and

Fig. 11 an end elevation of the parts shown in Fig. 2 showing the lock in the preliminary closing position.

50 In the drawings like numerals of reference

indicate corresponding parts in the different figures.

The machine with which my batter feeding device will usually be employed is of the ordinary type in which separable molds 55 having cores coöperating therewith are moved past a batter feeding device.

The form of the mold forms no part of the present invention, but as the lock therefor is used to actuate the batter feeding device a mold is shown in Figs. 1, 2 and 10 of the drawings.

Referring particularly to Fig. 1; 4 is a rotary carrier or disk on which the molds are carried. While my batter-feeding device may 60 be used to fill any form of mold, the mold shown is especially adapted for coöperation with my batter feeding device. In my construction each mold and core unit comprises the following parts: Each mold is formed 65 of a pair of separable sections 13 connected to arms 14 provided at their ends with the engaging hinge knuckles 15. 16 is a yoke-shaped bracket embracing the hinge knuckles 15. This bracket is secured to the carrier by 70 means of a screw 17 and also by means of a hinge pin 18, which extends through the jaws of the bracket, through the hinge knuckles 15 and through the carrier, being secured underneath by means of a nut and 75 above the upper jaw of the bracket by a pin 19.

The mold sections are preferably formed with a plurality of mold recesses with which coöperate the cores 20 secured to the core 85 arm 21, which arm is hinged behind the hinge pin 18 on lugs 22 formed on the bracket 16. From this arrangement it follows that by the removal of one screw and a nut, a mold and core unit is quickly and 90 easily removed or replaced whenever necessary. At the same time the arrangement of the yoke-shaped bracket always maintains the parts connected therewith in proper relationship, and the mold arms are as short as 95 possible, which tends to prevent them springing.

To assist in the proper alinement of the cores and molds, I prefer to continue the hinge pin upwardly as shown and to form 100

the core arm with a slot 23 embracing the hinge pin. The hinge pin also serves for the attachment of one end of one or more counterbalancing springs 24, the other ends of 5 which are secured to the arm 21.

The hinge pins 18 also serve to support the locking levers 25. Each locking lever is preferably forked to embrace the hinge pin to which it is pivoted at its upper end.

- 10 One end of each locking lever is provided with a projection 26 preferably formed as a roller adapted to engage in a slight indentation formed at the upper end of the arm 27 secured to the core arm. The other 15 end is adapted for engagement by locking or unlocking cams and is also preferably formed as a roller 28.

The cores are raised to the position shown in Fig. 1 by means of the cam 31 suitably 20 supported from parts not shown. This cam is adapted to engage over the projection 32, preferably formed as an anti-friction roller and secured to the heel of the core arm 21 behind its hinge. The mold sections are normally pressed to the closed position by 25 means of springs (not shown), and are opened to the position shown in Fig. 2 by special opening mechanism (not shown), the opening and closing means forming no 30 part of the present invention.

The mold sections must be firmly tightened together and locked closed during the filling of the molds and the cooking of the cones. It is also very desirable that the 35 locks be so arranged that the mold sections are not forced together in the event of a broken cone or other obstruction remaining between the parts, or otherwise the mold sections or closing mechanism might be 40 broken. It is also very important that no batter shall be fed to a mold which has not been properly closed. To accomplish the desired results I provide the following 45 mechanism.

On one section of each mold is pivoted a hook-shaped lock 43 which is adapted to engage over a pin 44 on the coöperating mold section. The hook is so shaped that it 50 will normally tend to fall to the preliminary closing position as shown in Fig. 11, with a slight shoulder 73 resting against the pin 44, requiring the application of force to press the lock to the final closing position and jam 55 the sections closely together. This force is applied through the medium of a stationary cam 45 supported from the frame of the machine in such a position that, as the mold travels toward it, it will engage, according 60 to circumstances, either below or above the center of a projection 46 on the lock, preferably formed as an anti-friction roller. If the lock has fallen to the preliminary locking position, as it will if there are no

obstructions in the mold, the end of the cam 65 will strike the roller just above the center and draw down the hook, thus tightly jamming the sections of the mold together. If there is any obstruction in the mold, the sections will be held apart, against the 70 tension of the closing springs, and the lock will fail to fall to the preliminary locking position, as shown in Fig. 10, in which case the cam 45 will either strike the roller below the center or pass completely beneath it, so that the lock is not actuated to force the sections together, and thus no breakage of the mold or locking mechanism will occur, due to the parts being forced together with 75 an obstruction between them. 80

The locks 43 are also used to actuate the batter-feeding device, the projection 47 being formed for that purpose. When a mold is properly locked, this projection occupies 85 the position shown particularly in Fig. 2, in which position it will engage and operate the batter-feeding device. If the mold be not completely closed, the projection 47 will occupy the position shown in Fig. 10, in 90 which it will not operate the batter-feeding device as will hereafter appear.

The batter-feeding device comprises a cylindrical casing 48 and the cylindrical batter-measuring device and valve 49 rotatable therein. The casing is provided with a flange 50 at each side adapted to be inserted in the grooved guides 51 formed at the lower end of the inwardly and downwardly projecting arms 52 extending from the support 53 formed on or secured to the frame of the machine. From the support 53 extends the rod 66. With the free end of this rod the valve 49 engages when the batter-measuring device is in the position shown in Fig. 6, the valve being thus held securely in position when the casing is positioned on the guides 51. A set screw 64 is preferably provided for clamping one of the flanges 50 in its grooved guide. 105

From this arrangement it follows that the batter-feeding device is readily placed in position or removed from the machine and disassembled in a few moments for cleaning 110 purposes.

The casing communicates by means of suitable feed openings with the hopper 55, which hopper is closed and provided with a pipe 56 which may be connected with any suitable source of batter supply. 115

As a plurality of mold recesses are employed in each mold, a plurality of inlet openings 57 may be employed in the top of the valve casing communicating with the hopper, though it is not essential to so separate them, and a plurality of discharge openings 58 are provided in the bottom of the casing. 120 125

The valve 49 is provided with a plurality of radial pockets 59 arranged in sets, the sets corresponding in number with the number of mold recesses in each mold. Each 5 radial pocket has an opening 60 through the periphery of the valve of less width than the width of the pocket (see particularly Figs. 3, 4, 5 and 6) which causes a proper cut-off of the batter and prevents drip. 10 From this arrangement it follows that the pockets are alternately filled and emptied as the valve is rotated, and as the filling and emptying occur during periods of movement, ample time is provided for proper filling and sufficient draining of the radial pockets followed by a cut-off of the drip before a fresh pocket arrives at the discharge position.

The end of the valve has a plurality of 20 dogs 61, corresponding in number to the radial pockets, pivoted thereon. The movement of each dog in the direction of rotation is, however, limited by the stops 62. When a mold approaches the batter-feeding device, 25 (see Fig. 2), the projection 47 and its lock, assuming the mold to be properly locked, will engage one of the dogs 61, press it against the stop 62 and then rotate the valve so that by the time the mold comes 30 to a rest, it is immediately below the discharge openings 58 and one of the sets of radial pockets is in position to discharge through the discharge openings of the casting. If the mold is not properly locked, the 35 projection passes by without engaging the proper dog to rotate the valve and no batter is fed, (see Fig. 10).

From the above description it will be seen that as each mold in turn reaches the batter 40 feeding device, it is filled as long as everything is going well. If, however, any mold becomes obstructed, the safety devices hereinbefore described come into operation and the machine makes no attempt to close the 45 obstructed mold and no batter is fed thereto.

It is desirable at times to be able to stop the operation of the batter feeding device, for example, when the molds and cores are being heated up at the beginning of operations. For this purpose I provide the 50 spring-pressed pin 68 slideable through the support 52. The pointed end of this pin, when projected toward the batter-feeding device, is adapted to engage the forward side 55 of any dog 61 which is in position to be engaged by a projection 47 of the lock of a properly locked mold and to push back the dog out of the path of the projection, (see Fig. 6). The stem of the pin has a cross 60 pin 69 passed through it which may be engaged with the end of the tube 70 through which the pin 68 passes to hold the pin back against the pressure of the spring and therefore out of operative position. The tube 70

is cut away at 71 to permit of the pin 68 being projected when the cross pin is brought into alignment with such cut out portions. An operating handle 72 is preferably connected to the pin 68.

What I claim as my invention is:—

1. In apparatus for the manufacture of ice cream cones, the combination of a rotatable carrier; a mold formed of a pair of separable sections connected to arms hinged on the carrier; spring means tending to close the molds; a hook-shaped lock pivoted on the end of one mold section; a pin on the other mold section with which the hook may engage, said lock tending to move into contact with the pin; a rotary batter feeding device; operating dogs pivoted thereon; stops limiting the swing of the dogs in the direction of rotation of the device; a projection on the lock adapted to engage one of said dogs to rotate the batter feeding device, the said projection being so located that it is only in operative position when the lock is in locking position.

2. In apparatus for the manufacture of ice cream cones, the combination of a rotatable carrier; a mold supported on the carrier; a rotary batter feeding device supported adjacent the pathway of the mold; operating dogs pivoted thereon; stops limiting the swing of the dogs in the direction of rotation of the device; and a part moving with the mold adapted to engage said dogs to rotate the batter feeding device.

3. In apparatus for the manufacture of ice cream cones, the combination of a support; arms extending outwardly and then downwardly from said support; grooved guides carried at the lower ends of said arms; a batter feeder casing provided with flanges adapted to slide into said grooves.

4. In apparatus for the manufacture of ice cream cones, the combination of a support; arms extending outwardly and then downwardly from said support; grooved guides carried at the lower ends of said arms; a batter feeder casing provided with flanges adapted to slide into said grooves; a rotary batter measurer and valve adapted to be fitted into the casing from one end; a rod extending from the support toward the guides adapted to engage the end of said valve when the casing is in position; and means for clamping the casing to one of the guides.

5. In apparatus for the manufacture of ice cream cones, the combination of a batter feeding device comprising a batter hopper, a batter feed pipe connected therewith; a cylindrical feeder casing having an opening in its top communicating with the hopper and a discharge opening in its bottom; a cylindrical batter measurer and valve fitted within the casing and provided with a

plurality of radial batter chambers, each chamber having an opening through the cylindrical wall of the valve of less width than the chamber and of substantially the same width as the openings in the casing.

6. In apparatus for the manufacture of ice cream cones, the combination of a rotatable carrier; a mold supported on the carrier; a rotary batter feeding device supported adjacent the pathway of the mold; operating dogs pivoted thereon; stops limiting the

swing of the dogs in the direction of rotation of the device; a part moving with the mold adapted to engage said dogs to rotate the batter feeding device; and a pin movable into the path of said dogs adapted to engage and hold out of operative position a dog otherwise in position to be operatively engaged by said part moving with the mold.

Signed at Toronto, Canada, this 3rd day of Sept., 1918.

LEWIS LEWISON.
